UNITED STATES PATENT OFFICE.

WILLIAM T. MOSS, OF SAN JOSE, CALIFORNIA.

POPCORN-CAKE MACHINE.

1,109,861.

Specification of Letters Patent.

Patented Sept. 8, 1914.

Application filed March 18, 1912, Serial No. 684,577. Renewed February 19, 1914. Serial No. 819,837.

To all whom it may concern:

Be it known that I, WILLIAM T. Moss, a citizen of the United States, residing at San Jose, in the county of Santa Clara and State of California, have invented a new and useful Popcorn-Cake Machine, of which the following is a specification.

The device forming the subject-matter of the present invention is adapted to be employed for the purpose of fashioning popcorn cakes, and the invention aims to provide a novel means for compacting the material into the pockets of a rotary carrier, and to provide means for lubricating the carrier to prevent an adhering of the material in the pockets of the carrier.

Another object of the invention is to provide in a device of this type, a roller, journaled above the carrier, and to provide means for lubricating the roller, to prevent the material within the carrier from adhering to the roller.

A further object of the invention is to provide novel means for adjusting the roller and the moistening or lubricating means, with respect to each other, and with respect to the carrier.

A further object of the invention is to improve generally, and to strengthen, devices of that type to which the present invention appertains.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings,—Figure 1 shows the invention in perspective; Fig. 2 is a transverse section on the line A—B of Fig. 1; Fig. 3 is a transverse section on the line C—D of Fig. 1; Fig. 4 is a fragmental vertical section showing certain of the supporting elements whereby the roller and the roller-moistening means are upheld; and Fig. 5 is a fragmental top plan of the platform.

In carrying out the invention there is provided a platform 1, which, if desired, may be supported upon legs 2, the platform 1 being covered upon its upper surface with a sheet of metal 3. Fixed to and up-

standing from the platform 1 is a shaft 4 upon which is journaled for rotation a circular carrier 5. Anti-friction rollers 6 are journaled in the platform 1 and uphold the carrier 5 adjacent its periphery. The carrier 5 is equipped at its periphery with a gear 7, meshing into a beveled pinion 8 secured to a shaft 9 journaled for rotation in a bearing 10 supported by the platform 1. Upon the shaft 9 there is a pulley 11, whereby the carrier 5 may be rotated by a prime mover. The shaft 9 terminates in a crank 12 whereby the shaft may be rotated manually.

In the carrier 5 there are a series of pockets 14, extended entirely through the carrier and located in a circle. In the platform 1 there is an arcuate outlet opening 15, located in the circle described by the pockets 14, the construction being such that the material in the pockets 14 may drop through the outlet opening 15.

Fixed to and upstanding from the platform 1 is a bracket 16 supporting a removable receptacle 17 provided with a spigot 18 adapted to discharge into the pockets 14. Located within the upper face of the metallic covering 3 is a loops-shaped groove 19, positioned adjacent the bracket 16, the groove 19 having a branch 20 in one end, communicating with an opening 21 extended through the platform 1 and through the covering 3. As shown in Fig. 5 the longer, side portions of the groove 19 are spaced apart sufficiently so that, when the carrier 5 is rotated, the pockets 14 may be passed between the said side portions. The water dripping from the spigot 18 into the pockets 14 will be caught by the drainage groove 19 and be carried into the opening 21 by the branch 20 of the groove.

Fixed to and upstanding from the platform 1, beyond the periphery of the carrier 5 there is a standard 22, provided with a longitudinal slot 23 in which is mounted a shaft 24 carrying a roller 25 beneath which the pockets 5 pass successively, when the carrier is rotated, there being a collar 26 upon the shaft, and a wing nut 26a upon the free end of the shaft to hold the same in adjusted positions along the standard 22. A collar 27 is attached to the opposite end of the shaft 24, the collar being slidable upon the shaft 4 and being held thereon by a binding screw 28. The inner end of the shaft 24 may, therefore, be adjusted synchronously

with the outer end of the shaft. A spring arm 30 is provided, the same having depending ends 31, slidably mounted in the standard 22 and in the shaft 4. Set screws 32, 5 threaded into the standard 22 and into the shaft 4, engage the ends of the spring arm 30, to provide for a vertical adjustment of the spring arm. The spring arm 30 carries a yieldable member, preferably a sponge 10 33, adapted to bear upon the periphery of the roller 25, to moisten the roller. The platform 1 carries a standard 35 from which projects a shaft 36, carrying a star wheel 37, the arms of which engage successively in 15 the pockets 14.

The operation of the device as hereinbefore described is as follows:—When rotary movement is imparted to the shaft 9, the beveled pinion 8, meshing into the gear 20 7 of the carrier 5, will cause a rotation of the carrier. As the carrier is rotated, the pockets 14 will pass successively in front of the operator, the operator filling the pockets with the material. The water contained 25 in the receptacle 17 will flow through the spigot 18 and drop into the pockets 14, thereby lubricating the pockets and preventing a sticking of the material therein. The said water will enter the groove 19 and pass by 30 way of the branch 20 through the drainage opening 21 in the platform 1. A continued rotation of the carrier 5 will cause each of the pockets 14 to pass beneath the roller 25, whereupon the material which is within each 35 pocket will be compacted therein. The roller 25 is prevented from sticking to the material, by reason of the fact that the sponge 33 is maintained moist, the sponge 33 engaging with the periphery of the roller 25. As the carrier 5 is rotated, the arms 40 of the star wheel 37 will engage successively in the pockets 14, thereby rotating the star wheel, and causing the arms of the star wheel to push the material in the pockets 14;

successively, through the slot 16 in the platform 1, thus securing an ejection of the finished product. By loosening the elements 28 and 26^a, the shaft 24 may be adjusted vertically with respect to the carrier 5, so that the roller 25 will coöperate properly 45 with the upper face of the carrier. The arm 31, being a resilient structure, will press the sponge 33 against the periphery of the roller 25. When the shaft 24 is adjusted vertically, in the manner hereinbefore set 50 forth, the spring arm 31, and consequently the sponge 33, may be adjusted vertically, likewise, by loosening the set screws 32.

Having thus described the invention, what is claimed is:—

In a device of the class described, a platform; a main shaft upstanding from the platform; a carrier rotatably supported by the shaft above the platform and provided with a pocket; a standard fixed to the platform; an auxiliary shaft supported terminally upon the standard and upon the main shaft for adjustment toward and away from the carrier; means for holding the auxiliary shaft in adjusted positions along the main shaft and the standard; a roller carried by the auxiliary shaft and adapted to bear upon the carrier; a spring arm terminally mounted on the main shaft and on the standard for adjustment toward and away 65 from the roller; a moistening device supported by the arm and yieldably pressed by the arm against the roller; and means for holding the spring arm in adjusted positions upon the main shaft and the standard. 70 75 80

In testimony that I claim the foregoing as my own, I have hereto affixed my signature in the presence of two witnesses.

WILLIAM T. MOSS.
